DESIGN FOR A TOY TRANSIT

Elmer M. Knudsen and Arthur Russell Maier,
Webster Groves, Mo.

Application May 3, 1946, Serial No. 129,269

Term of patent 7 years

(Cl. D34—15)

To all whom it may concern:

Be it known that we, Elmer M. Knudsen and Arthur R. Maier, citizens of the United States and residents of Webster Groves, in the county of St. Louis and State of Missouri, have invented a new, original, and ornamental Design for Toy Transit, of which the following is a specification, reference being had to the accompanying drawing, forming part thereof.

Fig. 1 is a side elevational view of a toy transit, showing my new design.

Fig. 2 is a similar view on a large scale of the upper portion of the transit,

Fig. 3 is a rear end elevational view of the upper portion of the transit,

Fig. 4 is a front elevational view of the upper portion of the transit,

Fig. 5 is a side elevational view of the upper

portion of the transit, looking at the opposite side from that shown in Fig. 2,

Fig. 6 is a top plan view; and

Fig. 7 is a horizontal cross-sectional view on the line 7—7 in Fig. 2.

We claim:

The ornamental design for a toy transit, as shown and described.

ELMER M. KNUDSEN.

ARTHUR RUSSELL MAIER.
